UNITED STATES PATENT OFFICE.

JAMES S. GOODWIN, OF EMERALD, WISCONSIN.

MAIL-BAG FASTENING.

SPECIFICATION forming part of Letters Patent No. 399,986, dated March 19, 1889.

Application filed February 6, 1888. Serial No. 263,077. (No model.)

To all whom it may concern:

Be it known that I, JAMES S. GOODWIN, a citizen of the United States of America, residing at Emerald, in the county of St. Croix and State of Wisconsin, have invented certain new and useful Improvements in Mail-Bag Fastenings, of which the following is a specification, reference being had therein to the accompanying drawings.

10 This invention relates to improvements in mail-bag fastenings; and it consists in the construction and combination of the parts hereinafter described, whereby time is saved in the adjusting of the parts, the locking-chain is rendered easier of manipulation, the staples holding the said chain are rendered firmer in their position, and the bag is locked by a simple and efficient means.

15 In the drawings, Figure 1 is a side elevation of a mail-bag provided with this invention. Fig. 2 is a plan view of the lock for fastening the end of the chain. Fig. 3 is a vertical elevation of the interior of the lock. Fig. 4 is a detail view of a modification of the 20 clamping-jaws of the same. Fig. 5 is a section cut through the upper edge of the said bag, upon which the flap is folded.

25 The letter A designates a mail-bag of ordinary shape, which is provided at the upper edge, C, upon which the flap B folds, with a double thickness of leather, which consists of a piece the length of the said flap, which is folded back on the side of the bag to which it is attached and riveted at the lower edge 30 to the same. Interposed between this additional thickness and the side of the bag is a rubber strip, D. The said strip is of any weight desired, and when placed in position materially stiffens the said edge, but does not become rigid with the action of the weather. Placed at short intervals in the center of the 35 said edging are the staples E. The said staples are formed to a point in the center, and are provided upon either end with the forks F F, the prongs of which are joined by the shoulders G. In mounting the said staples upon the bag, as aforesaid, holes are bored in the same to receive the prongs of the forks F F, which are then passed through, their ends 40 extending upon the other side. The small washers H are then placed over the protruding ends, which are then headed, as in the

ordinary riveting. By means of thus mounting the said staples upon the bag they are kept more firmly in an upright position, as 55 the washers H and the shoulders G bear firmly against the opposite sides of the leather of the bag, in which position the staples E are forced to remain perpendicular to their part of the leather to which they are attached. 60 Passing through the said staples is the chain I, the end of which is rigidly attached to the back of the bag. I construct the said chain of one or more small chains joined together at the ends and covered with leather, whereby 65 they are more readily handled and passed through the staple E. At the one end the said chain is provided with a perforated head, J, by means of which it is secured rigidly to the leather at the back of the said bag. At 70 the other end it is provided with a barbed head, K, to which it is attached by means of the riveted pin L, passing through a perforation in the rear of the same. The said chain may be constructed any shape desired; but I 75 preferably use the flat-shaped chain shown in the accompanying drawings.

Secured rigidly to the leather upon the back of the bag by means of rivets passed through the said leather and perforations in the flat 80 plate M is the casing of the lock X. The said casing is secured to the plate M by means of the bolts N and the pins O O and P P, the latter of which are provided with heads extending above the said casing to act as stops 85 for the shield of the key-hole of the lock. It is provided, further, at the forward end with the square perforation R, adapted to allow the barbed end of the head K to pass freely. Mounted in the said casing and extending 90 around the bolts N and resting between the pins O O is the spring-clutch S. In thus mounting the said clutch between the pins O O, I prevent the wearing of the same where it is mounted around the bolt end. Thereby, when 95 opening at the free end, this construction brings the springing strain upon the straight arms of the said spring. It is provided upon the end with the opposed hooked ends T T, which are adapted to fit over the barbed end 100 of the head K, and, when resting together, presenting beveled heads toward the perforation R. Pivoted mounted between the arms of the said spring is the double dog U, the

curved surface S of which rests against the inside of the said arms. The said dogs may be provided with any suitable means for retaining them out of engagement with the key, 5 as in a Yale lock, by means of which the said dogs are turned so as to spread the said arms. The casing directly over the said dogs is provided with a slot for the insertion of a key wherewith to operate the said dogs, a shield, 10 V, being provided therefor, having the stops V' and V' upon either side of the same, to prevent the said shield from turning completely around while the bag is being handled.

In fastening the said bag the flap B is 15 brought down over the edge E, the same being held rigidly in an upright position, as hereinbefore described. The chain I is then passed through the said staples, over the flap, and around to the back of the said bag. The 20 barbed head K is then inserted in the perforation R in the casing, striking between the beveled faces of the opposed arms of the spring S, pressing them apart, and passing the barbed end of the head K behind the locked ends of 25 the said opening, which falls into position behind the same. In this position it is impossible to withdraw the barbed end of the head K without spreading the arms of the spring S. This is done by removing the shield V 30 and inserting the said key into the said dogs and turning the same, thereby spreading the arms of the spring far enough apart to permit of withdrawing the barbed head K.

By means of this construction the operation 35 of locking and unlocking a bag consumes a very little time. When thus unlocked, the chain can be drawn through the staples E with ease and rapidity, the leather preventing the catching of any of the parts 40 or the jamming of the same. The said dogs are not turned completely around, being prevented by the arms of the spring S striking against the pin P, so that when the barbed head K is withdrawn from the engagement 45 with the hooked ends of the said arm and the keys operating the dogs are released the said dogs are forced into their normal position, the hooked ends of the said arm resting against each other. When the chain is thus 50 withdrawn, the flap B is raised out of engagement with the staples E and the bag is open for manipulation.

While I have described the construction of the edge C to consist in placing a stiff material—such as rubber—between the pieces of leather, it is obvious that I can change the construction by placing the gum or stiff material either upon the outside or inside of the

same without altering the scope of the invention. 60

The modification shown in Fig. 4 of drawings is used when the arms of the spring-clutch S are made from wrought-iron or cast-steel in two halves and mounted upon the bolt N, so as to revolve about the same. About 65 the outsides of the rear ends of the said arms is placed the spring W, which tends to throw the barbed ends of the said arms together, as described with reference to the arms of the spring S. This modification may be used to 70 advantage in many parts of the country where the climate or sudden changes of temperature are hard upon the spring metal, tending to break the same, and in this case the clutch-arms herein shown could be more readily 75 changed and are cheaper of construction than that shown in the other figures.

What I claim is—

1. In a mail-bag such as described, the combination of the staples E, secured in position 80 around the said bag and adapted to extend through perforations provided in the flap, a chain, I, for extending through the said staples, consisting of a number of small chains secured together and the whole covered with 85 a flexible material to prevent the chain catching in the staples, and a lock, X, for securing the ends of the chain together, substantially as described.

2. In a mail-bag such as described, the combination of the staples E, secured in position upon the bag and extending through perforations provided in the flap, a chain, I, adapted to pass through the said staples and provided upon the end with a barbed head, K, and a 95 lock to receive and hold the said head, consisting of two arms, S, the rear ends of which are formed to a semicircle to engage a post, N, upon which they turn, and the front ends are formed to hooks T, the barbs of which 100 meet to close behind any protuberance passed between them, the spring W, passed around the post N outside the arms S and extending along the sides of the same, the pins O O, placed to retain the spring W in position to 105 maintain a pressure upon the arms S, and the double dog U, pivoted between the arms S and adapted to spread the same, substantially as described.

In testimony whereof I affix my signature in 110 presence of two witnesses.

JAMES S. GOODWIN.
